F. L. MANNY,
FOLLOWER FOR FILING TRAYS.
APPLICATION FILED MAY 29, 1916.

1,226,791.

Patented May 22, 1917.

UNITED STATES PATENT OFFICE.

FRED L. MANNY, OF BENTON HARBOR, MICHIGAN, ASSIGNOR, BY MESNE ASSIGNMENTS, TO BAKER-VAWTER COMPANY, OF BENTON HARBOR, MICHIGAN, A CORPORATION OF MICHIGAN.

FOLLOWER FOR FILING-TRAYS.

1,226,791.

Specification of Letters Patent. Patented May 22, 1917.

Application filed May 29, 1916. Serial No. 100,439.

To all whom it may concern:

Be it known that I, FRED L. MANNY, a citizen of the United States, residing at Benton Harbor, in the county of Berrien and State of Michigan, have invented certain new and useful Improvements in Followers for Filing-Trays, of which the following is a specification.

My invention relates to an adjustable back or follower adapted to be slidably moved from front to rear of a tray or box, such as trays ordinarily used as card index containers, or for filing cabinets, for the reception and classification of letters, or bills, or other documents, in accordance with methods now largely followed in commercial establishments. The object of my invention is the provision of simple and effective adjusting mechanism adapted to permit the back plate to move freely in a forward direction, but arranged to automatically lock the plate against rearward movement except when a releasing member is operative to permit such movement. With this object in view I have devised the mechanism illustrated in the accompanying drawings and hereinafter described in detail, and my invention consists in the arrangement and organization of coöperating parts, the essential elements thereof being more particularly pointed out in the appended claims.

Figure 1 of the drawings is a perspective of a filing tray provided with a follower or adjustable back to which my invention is applied; Fig. 2 is a cross-section of the tray and follower track, looking toward the rear of the box, with the follower shown in elevation; Fig. 3 is a detail on the line 3—3 of Fig. 2, illustrating part of the gripping mechanism; and Fig. 4 is a bottom plan view of a portion of the gripping and grip-releasing mechanism of the follower.

The same reference characters indicate the same parts in all the figures of the drawing.

My invention may be embodied in an adjustable follower or back such as is used in many different kinds of boxes to vary the space in front of the follower, and support the contents properly, whether the box be nearly empty or full. For purposes of illustration and description I have chosen a well known form of tray, such as is used as the drawer of a cabinet for the reception of the

cards of a card index system, or sheets of similar character. To adapt the drawer for the employment of my invention, there is secured to the bottom thereof a track, or slideway, which in the present instance consists of a strip of sheet metal 1, bent upwardly to form sides 2, and bent inwardly at the top of the sides to form overhanging retaining flanges 3.

The follower consists of an inclined plate 4 mounted upon a slide arranged to run in the slideway and carrying gripping mechanism whereby it may be secured in any adjusted position. This plate, indicated by the reference numeral 4, may be conveniently formed out of sheet metal, and is provided at the top, as shown, with a rearwardly bent flange 5, and in the present instance, though not necessarily, is formed at the bottom with rearward attaching flaps 6 brazed or otherwise secured to horizontal flange or supporting strip 7. The slide 8 upon which the plate 4 is mounted, consists of a metal base 9 formed with downwardly directed flanges 10 at its sides, and an upward inclined tongue 11 to which the plate is brazed or otherwise secured, and on each side of the tongue a forwardly extending runner 12 which is continuous with the flange 10 and a narrow adjacent portion of the base 9. The flanges 10 are similarly cut away to form opposite wedge-shaped recesses having an inclined wedging face 13 rising from front to rear and terminating at a perpendicular rear wall 13^a at the widest part of the recess. Confined between the opposite sides 2 of the slideway, and between the wedging faces 13 of the slide and the bottom of the slideway, (see Figs. 3 and 4) is arranged a roller 14 which constitutes a clutch member for frictionally binding the slide in the slideway. This roller is normally pulled forwardly by a light spring, and the proportion and arrangement of the parts are such that it will lie in frictional contact with the wedging faces 13 and the bottom of the slideway at a point near or somewhat forward of the center of such wedging faces. Manually operable means for forcing the roller rearwardly into inoperative position in the wider parts of the recesses are provided, consisting of a pair of (spring-pressed) rods 15, 15, rotatably mounted in the top flange 5 of the follower plate and the supporting strip 7, and pro-

vided with cams 16 at their bottom ends adapted to force the roller rearwardly when the rods are rotated. The rods are under spring tension, in the present instance 5 through a common spring 17, tending to maintain the cams out of contact with the roller, and their tops are bent and constructed to serve as a pair of finger pieces 18, which may be forced toward each other 10 when grasped between the thumb and forefinger in order to rotate the rods and shift the roller rearwardly as above described.

It is obvious that with the construction and arrangement of parts which have been 15 described, the follower cannot be forced rearwardly by any pressure upon it, since such movement would tend to roll the roller toward the narrower part of the recesses in the flanges 10 of the slide, and the slide 20 would therefore only the more tightly engage the overhanging flanges 3 of the slideway. Upon manipulation of the finger-pieces 18 of the releasing mechanism, however, the roller will be shifted into inoperative position, where it can exert no wedging 25 action between the slide and the bottom of the slideway, and the slide and follower can therefore be shifted freely.

While, as above described, the follower 30 cannot be shifted rearwardly from any given position without operating the releasing mechanism, it may be shifted forwardly, the roller in such case tending to roll into the wider end of the recess and exerting no restraining effect beyond a very slight braking action. This is of advantage, 35 since the follower may be readily shifted forwardly without attention to the releasing mechanism, and there is never any inside 40 pressure tending to displace it in such direction to be guarded against.

It is evident that changes may be made in the proportion of parts and the specific form and construction of parts without departing 45 from the principles of my invention as above described, and the appended claims are therefore not limited further than required by their terms to the exact structure herein shown.

50 I claim:

1. In combination with a tray provided with a central bottom slideway, a follower equipped with a slide member adapted to run in said slideway and formed with an 55 inclined wedging surface, a roller arranged to coöperate with the wedging surface of the slide and with the slideway, and means for shifting the roller out of coöperative relation.

60 2. In combination with a tray provided with a central bottom slideway, a follower equipped with a slide member adapted to run in said slideway and formed with an inclined wedging surface, a spring-pressed 65 roller arranged to normally yieldingly en-

gage the wedging surface of the slide and the bottom of the slideway, and manually operable means for shifting the roller out of coöperative relation with said wedging surface and said slideway.

70 3. In combination with a tray provided with a central bottom slideway, a follower equipped with a slide member adapted to run in said slideway and formed with an inclined wedging surface, a spring-pressed roller arranged to normally yieldingly engage the wedging surface of the slide and the bottom of the slideway, and a pair of manually operable spring-pressed pivoted rods equipped with cams arranged to engage 75 said roller and shift it out of coöperative relation with said wedging surface and said slideway.

80 4. In combination with a tray provided with a central bottom slideway having a bottom and side faces and overhanging retaining flanges, a follower including a sliding member formed with downwardly turned flanges, said flanges being formed with opposite recesses having wedging faces, 85 and a roller extending between the side faces of the slideway and arranged to coöperate with the wedging faces of the flange recesses and the bottom of the slideway.

90 5. In combination with a tray provided with a central bottom slideway having a bottom and side faces and overhanging retaining flanges, a follower including a sliding member formed with downwardly turned flanges, said flanges being formed with opposite recesses having wedging faces, 95 a spring-pressed roller extending between the side-faces of the slideway and arranged to yieldingly engage the wedging faces of the flange recesses and the bottom of the slideway, and manually operable means for disengaging the roller.

100 6. In combination with a tray provided with a central bottom slideway, a follower equipped with a sliding member adapted to run in said slideway, a roller constituting a clutch and coöperating with said sliding member and said slideway, and means for shifting said roller comprising a pair of pivoted rods equipped at their tops with 105 finger pieces and having their bottom ends arranged to coöperate with said roller.

110 7. In combination with a tray provided with a central bottom slideway, a follower equipped with a sliding member adapted to run in said slideway, a roller constituting a clutch and coöperating with said sliding member and said slideway, and means for shifting said roller comprising a pair of pivoted rods equipped at their tops with finger 115 pieces and equipped at their bottom ends with cams arranged to engage the opposite ends of said roller.

120 8. In combination with a tray provided with a central bottom slideway having a 125

bottom and side faces and overhanging retaining flanges, a follower including a sliding member formed with downwardly turned flanges, said flanges being formed with opposite recesses having wedging faces, a spring-pressed roller extending between the side-faces of the slideway and arranged to yieldingly engage the wedging faces of the flange recesses and the bottom of the slideway, and a pair of pivoted spring-pressed operating rods equipped with cams at their lower ends arranged to engage the opposite ends of said roller.

9. In combination with a tray provided with a slideway, a follower including a plate

formed with a rearwardly bent top flange and a rearwardly extending horizontal flange at its bottom and equipped with a sliding member adapted to run in said slideway, a roller constituting a clutch and co-operating with said sliding member and said slideway, and a pair of spring-pressed operating rods pivotally mounted in said flanges and equipped at their tops with finger pieces and arranged to shift said roller. 20
